US0D1023004S

(12) **United States Design Patent** (10) Patent No.: **US D1,023,004 S**
(45) Date of Patent: ** Apr. 16, 2024

(54) **RFID READER**

(71) Applicant: **CANON KABUSHIKI KAISHA**,
Tokyo (JP)

(72) Inventor: **Yoshihiro Miyazawa**, Tokyo (JP)

(**) Term: **15 Years**

(21) Appl. No.: **35/515,914**

(22) Filed: **Dec. 13, 2022**

(80) **Hague Agreement Data**

Int. Filing Date: **Dec. 13, 2022**

Int. Reg. No.: **DM/225752**

Int. Reg. Date: **Dec. 13, 2022**

Int. Reg. Pub. Date: **Dec. 30, 2022**

(30) **Foreign Application Priority Data**

(57) **CLAIM**

The ornamental design for an RFID reader, as shown and described.

DESCRIPTION

1. RFID reader

1.1 : Front

1.2: Back

1.3:Top

1.4 : Bottom

1.5 : Left

1.6 : Right

1.7 : Perspective

This product is an RFID (Radio Frequency Identification) reader that reads information recorded in a tag by wireless communication.
